UNITED STATES PATENT OFFICE.

THOMAS J. KEHOE, OF TOLEDO, OHIO, ASSIGNOR TO THE WILLYS-OVERLAND COMPANY, OF TOLEDO, OHIO, A CORPORATION OF OHIO.

WINDOW-LIFTING DEVICE.

Application filed March 29, 1917. Serial No. 158,194.

To all whom it may concern:

Be it known that I, THOMAS J. KEHOE, a citizen of the United States, residing at Toledo, county of Lucas, State of Ohio, have 5 invented new and useful Improvements in Window-Lifting Devices, of which the following is a specification.

This invention relates to enclosed bodies for carriages or motor vehicles, and more 10 particularly to improvements in window operating devices therefor.

The principal object of this invention is to provide a simple, positive, and efficient window operating device, whereby the window 15 may be raised or lowered to any desired position, and automatically locked in such position.

Further objects, and objects relating to economies of manufacture and details of 20 construction, will definitely appear in the detailed description to follow.

I accomplish the objects of my invention by the devices and means described in the following specification and my invention is 25 clearly defined and pointed out in the appended claims.

A structure constituting a preferred embodiment of my invention is illustrated in the accompanying drawing, forming a part 30 of this specification, in which:

Figure I is a transverse sectional view of a vehicle door showing a preferred form of my invention attached thereto;

Figure II is a fragmentary elevational 35 view of my window operating device attached to the sash;

Figure III is an enlarged sectional view taken substantially on line 3—3 of Figure II showing the automatic lock and driving 40 means for the driving sprocket;

Figure IV is an enlarged sectional view taken on line 4—4 of Figure II, showing the driven sprocket and automatic take-up for the driving chain;

Figure V is a detail sectional view taken 45 on line 5—5 of Figure II.

Figure VI is a fragmentary elevational view of the driven sprocket taken on line 6—6 of Figure IV;

Figure VII is a perspective view of the 50 handle grips;

Figure VIII is a detail sectional view taken on line 8—8 of Figure III showing the handle grips and their mounting; and

Figure IX is an elevational view of the 55

driving sprocket taken on line 9—9 of Figure III.

In the drawings, similar reference characters refer to similar parts throughout the several views and the sectional views are 60 taken looking in the direction of the little arrows at the ends of the section lines.

Considering the numbered parts of the drawings; 1 represents a vehicle door of any standard construction, and 2 the window sill 65 integral therewith. The glass panel 3 is slidably mounted in ways 4 at the sides of the door 1, the glass panel being adapted to be raised or lowered, and is so operated by my improved operating device, the description of which is as follows:

My improved mechanism is mounted on a spacing bar 5, (Figs. II and III), which is secured to the door 1 by means of the cross plates 6. The upper end of the spacing bar 5 has an offset portion 7 and on the opposite side of the offset portion 7 is an offset portion 8, welded or otherwise secured to the said spacing bar, these two offset portions 7 and 8 forming a fork to support the 80 driving sprocket 9. At the lower end of the spacing bar 5 is slidably mounted a driven sprocket 10, the same being connected with the driving sprocket 9 by the driving chain 11. Driving sprocket 9 is brazed or otherwise secured to a hub 12. Loosely journaled on the hub 12 are circumferentially grooved bearings 13 and 14, the same resting in the forked ends 15 of the offset portions 7 and 8 of the spacing bar 5. The hub 12 is counterbored at 16 to receive a post 17 having an enlarged end portion 18 at its inner end, and is secured at its outer end by the cotter pin 20. Mounted on the post 17 is a spring 19, one end of which abuts against the enlarged 95 end 18 of the post 17, and the other end against the offset portion 12' of the hub 12, thus drawing the driving sprocket and hub into locked position. The driving sprocket 9 has a series of holes 21 adapted

to be engaged by the stop pin 22, which is mounted on the offset portion 7 of the spacing bar 5. It will be seen that as the parts are in their normal position and the stop pin 22 engages one of the holes 21, the driving sprocket 9 is held in locked position against rotation and the sash 3 will stay in the desired position where set.

At the lower end of the sash 3 is mounted a metal binding strip 23, to the lower side of 110

which is secured an angle bar 24. A plate 25 is secured to the inner side of the angle bar 24 by screws 26. A U shaped member, or special link, 27, is substituted for one of the links of the chain 11, the member 27 being connected to the links at either side and operated in the same manner as an ordinary link in the operation of the chain passing over the sprocket 9. The member 27 is provided with a spindle or pin 28 projecting laterally therefrom. The spindle or pin 28 has enlarged portions 29 thereon, thus forming a circumferential grooved portion which is slidably mounted in the slot 30 of the plate 25. To disconnect the driving mechanism from the sash I provide an enlarged opening 31 at one end of the slot 30, so that the outer enlarged portion 29 of the spindle 28 may be slipped through, thus disconnecting the parts 20 just described.

For convenience in turning the driving sprocket and connected parts, I provide handle grips 32 and 32', the handle grip 32 being provided with a threaded end 33 which is 25 adapted to be screwed into a corresponding threaded portion 34 of the handle grip 32'. To hold the handle grips in locked position after they have been screwed together, the grips 32 and 32' have flattened surfaces 35, 30 which are engaged by the end of the screw or lock nut 36, as clearly appears in Figure VIII. As the flat end of nut 36 engages the flat surfaces 35, and the side of the nut engages shoulders 35' formed on the grips, the 35 grips cannot be unscrewed or slid in the hub 12 when the nut 36 is in place. It is of convenience in mounting the window operating device to the door, to have the handle grips demountable, as the upholstery 37 on the inner side of the door 1 may be closely fitted around the hub 12 before the grips are mounted in position, thus giving a neat appearance to the inside of the body of the door.

40 To insure the driving chain 11 against rattle and to hold the same taut the driven sprocket 10 is slidably mounted on the spacing bar 5, the sprocket 10 being mounted in a fork 38, (see Figures II and IV). The sprocket may be mounted in the fork 38 in 45 any desired manner, but I preferably provide balls 39 and ball race 40, the same being secured by the locking pin 41. The spacing bar 5 has two depending arms 42 slidably mounted in recesses or grooves 43 in the side of the fork 38. The upper end 44 of the fork 38 is slotted at 45 to receive the spacing bar 5. Mounted on the member 44 is a spring 46, one end of which rests against the shoulder 38' of the fork 38, and the other end against the washer 47. This spring 46 has a tendency to push the fork 38 and its connected part downwardly thus forming tension on the driving chain 11, so that at all times the 60 chain is kept taut to insure that it will not

swing and strike against the sides of the door and produce an objectionable rattle.

To operate my improved device the handle is first pulled forwardly thus releasing the driving sprocket 9 from the stop 22 at 70 which time the sprocket and its connected parts may be rotated in either direction thus raising or lowering the window as desired. When the sash is placed in the desired position, the handle is released and one of the 75 holes 21 engages with the stop pin 22, thus holding the window in fixed position.

I am aware that the embodiment of my invention here shown and described is susceptible of considerable variation without 80 departing from the spirit and scope thereof and, therefore, I desire to claim the same broadly as indicated by the appended claims. I have found, however, that this particular embodiment is desirable from many standpoints and, therefore, I desire to claim the same specifically as well as broadly as will appear from the appended claims. 85

Having thus described my invention, what I claim as new and desire to secure by Letters Patent is:

1. In a window lifting device, the combination with a movable member and a driving chain for actuating the same; of a sprocket for operating said chain; means 95 normally locking said sprocket; and a device for first moving said sprocket axially to release the same and then rotating the sprocket to operate the chain.

2. In a window lifting device, the combination with a movable member and a driving chain for actuating the same; of a sprocket for operating said chain; a stud co-operating with openings to normally lock the sprocket; and a device for first moving 105 said sprocket axially to disengage the stud from one of said openings and then rotating the sprocket to operate the chain.

3. In a window lifting device, the combination with a movable member and a driving chain for actuating the same; of a sprocket for operating said chain; means normally locking said sprocket; and a handle given a lateral movement to move the sprocket axially to release the same and given 110 a rotating movement to rotate the sprocket.

4. In a window lifting device, the combination with a movable member and a driving chain for actuating the same; of a sprocket for operating said chain and provided with openings; a fixed stud co-operating with the openings in said sprocket to normally lock the latter; and a handle given a lateral movement to move the sprocket axially to release the same and given a 120 rotating movement to rotate the sprocket.

5. In a window lifting device, the combination with a movable member and a driving chain for actuating the same; of a sprocket for operating said chain; means 130

- normally locking said sprocket; spring means normally retaining said sprocket in locked position; and a device for first moving said sprocket axially against the tension of said spring means to release the sprocket and then rotating the sprocket to operate the chain.
6. In a window lifting device, the combination with a movable member and a driving chain for actuating the same; of a sprocket for operating said chain and provided with openings; a fixed stud cooperating with the openings in said sprocket to normally lock the same; spring means normally retaining said sprocket in locked position; and a device for first moving said sprocket axially against the tension of said spring means to release the sprocket and then rotating the sprocket to operate the chain.
7. In a window lifting device, the combination with a movable member and a driving chain for actuating the same; of a sprocket for operating said chain; means normally locking said sprocket; a handle given a lateral movement to move the sprocket axially to release the same and given a rotating movement to rotate the sprocket; and spring means for moving the handle and sprocket axially when the handle is released to move the sprocket into locking position.
8. In a window lifting device, the combination with a movable window and a driving chain for actuating the same; of a sprocket for operating said chain and provided with openings; a fixed stud co-operating with the openings in said sprocket to normally lock the latter; a handle given a lateral movement to move the sprocket axially to release the same and given a rotating movement to rotate the sprocket; and spring means for moving said handle and sprocket axially when the handle is released to move the sprocket into locking position.
9. In a window lifting device, the combination of a movable window, a forked frame, spaced bearings carried by the forks of the frame, a spring pressed actuating member slidably and rotatably mounted in said bearings, a sprocket secured upon said actuating member, means adapted to normally lock the sprocket against rotation and adapted to release the same upon longitudinal movement of said actuating member, and means operatively connecting the sprocket with the window to effect the raising and lowering of the same upon rotation of said sprocket.
10. In a window lifting device, the combination of a movable window, a pair of spaced rotatable members one of which is mounted for axial movement, locking means releasably engaging said axially movable member to permit rotation of the same, a belt connecting said rotatable members, means connecting said belt with said window to effect movement of the same in opposite directions, and means for rotating said axially movable member.
11. In a window lifting device, the combination of a movable window, a pair of sprockets, a support for one of the sprockets, a fork in which the other sprocket is mounted, a forked frame member in which said fork is slidably and yieldably mounted, a chain connecting said sprockets, means connecting the chain with said movable window and means for actuating one of said sprockets.
12. In a window lifting device, the combination of a movable window, a pair of forked members one of which is yieldably mounted upon the other, a sprocket carried by each of said members, a chain connecting said sprockets, means connecting the chain with said window and means adapted to rotate one of said sprockets.

In witness whereof I affix my signature.
THOMAS J. KEHOE.
